Primary Examiner — Justin M Jonaitis*Assistant Examiner* — Natalya M Rapundalo(74) *Attorney, Agent, or Firm* — EcoTech Law Group, P.C.(57) **CLAIM**

The ornamental design for a flask as shown and described.

DESCRIPTION

FIG. 1 is an exploded top perspective view of a flask showing our new design;

FIG. 2 is an exploded bottom perspective view thereof;

FIG. 3 is a top perspective view of the flask shown in an assembled configuration;

FIG. 4 is a front side view thereof;

FIG. 5 is a back side view thereof;

FIG. 6 is a top side view thereof; and,

FIG. 7 is a bottom side view thereof.

The broken lines in the drawings depict portions of the flask that form no part of the claimed design.
